PLAYGROUND FERRIS WHEEL

Claude W. Ahrens, Grinnell, Iowa

Filed Jan. 13, 1961, Ser. No. 63,547

Term of patent 14 years

(Cl. D34—5)

Fig. 1

Fig. 2

Fig. 3

Fig. 4

FIG. 1 is a perspective view of a playground ferris wheel showing my new design;

FIG. 2 is an elevational view of one side of the ferris wheel, with the opposite side being identical thereto;

FIG. 3 is an elevational view of the other side of the ferris wheel, with the opposite side being identical thereto; and

FIG. 4 is a top plan view of the ferris wheel.

I claim:

The ornamental design for a playground ferris wheel, substantially as shown and described.
